CONTROL MEANS FOR LIQUID SUPPLY SYSTEMS

Harry B. Holthouse, Chicago, Ill., assignor to Galvin Manufacturing Corporation, Chicago, Ill., a corporation of Illinois

Application June 15, 1942, Serial No. 447,053

8 Claims. (Cl. 158—28)

1

This invention relates generally to control means for a liquid supply system and in particular to a fuel system for apparatus having a combustion portion in which the rate of fuel feed to the combustion portion is controlled in response to the heat radiated therefrom.

An object of this invention is to provide improved heat responsive means for controlling the rate of liquid flow in a liquid supply system.

Another object of this invention is to provide a protective system for controlling the rate of fuel feed to the combustion portion of apparatus of internal combustion type in response to the heat radiated from such combustion portion.

A further object of this invention is to vary the rate of fuel feed to the combustion portion of heating apparatus relative to the heat radiated from the combustion portion.

Still another object of this invention is to control the rate of fuel feed to the combustion portion of air heating apparatus in response to the temperatures of the air to be heated and of the heat radiated from the combustion portion.

A feature of this invention is found in the provision of a fuel supply system including a pump and fuel line for apparatus having a combustion portion, in which the system is arranged in a heat exchange relation with the combustion portion and has a heatable mass which is large relative to the amount of fuel flowing therethrough so as to transfer heat to such fuel. On heating of the system above a certain temperature a vapor lock condition is produced in the pump which reduces the rate of fuel feed to the combustion portion.

Another feature of this invention is found in the provision of a fuel supply system for air heating apparatus having a combustion portion, in which a pump in the fuel system is arranged to be heated by the combustion portion. The air to be heated is directed about the pump and is at a temperature to normally cool the same. On heating of the air circulated about the pump above a normal cooling temperature the temperature of the pump is increased to a value which vaporizes the fuel therein so that a vapor lock condition is produced in the pump which reduces the rate of fuel feed to the combustion portion.

Further objects, features and advantages of this invention will become apparent from the following description when taken in connection with the accompanying drawings in which:

Fig. 1 is a perspective view of an air heating apparatus embodying the fuel supply system of this invention;

2

Fig. 2 is a transverse sectional view of the apparatus of Fig. 1 with the combustion portion thereof shown in development for the purpose of clarity;

Fig. 3 is a transverse sectional view of the combustion portion of the heating apparatus as seen along the line 3—3 in Fig. 2;

Fig. 4 is a longitudinal sectional view of the fuel pump included as a part of the fuel supply system of this invention;

Fig. 5 is a transverse sectional view as seen along the line 5—5 in Fig. 4; and

Fig. 6 illustrates diagrammatically a control circuit for the heater apparatus in Figs. 1 and 2.

The invention is illustrated in the drawings as applied to an air heating apparatus for controlling the rate of fuel feed to a combustion portion therefor in response to the heat radiated from the combustion portion. The heating apparatus includes a combustion compartment for the combustion portion, and a mechanical compartment arranged adjacent to the combustion compartment so as to be in a heat exchange relation therewith. Located within the mechanical compartment and adapted to be heated therein is a fuel supply system for the combustion portion including a fuel pump and a fuel line. The heatable mass of the system is such that the heat therefrom is transferred to the fuel flowing therein. The air to be heated initially flows through the mechanical compartment to cool the parts therein prior to passing in a heat exchange relation with the combustion portion. On heating of this air to a value above a normal cooling temperature its cooling function is reduced concurrently with an increase in the heat radiated from the combustion portion, by virtue of such increased temperature, to provide in all for a heating of the fuel supply system above a normal operating temperature. The same action is accelerated relative to the heating of the fuel system, should the flow of air to be heated be entirely stopped.

The increase in the temperature of the fuel system above its normal operating temperature effects a vaporization of the fuel in the pump to produce a vapor lock condition therein which reduces the rate of fuel feed to the combustion portion and in turn the heat generated therein.

On a continued heating of the fuel system above a normal operating temperature the vapor lock action is continuously increased to a point at which the operation of the combustion portion is practically stopped. This arrangement of the fuel supply system relative to the associated com-

burstion portion thus provides a protective system which acts to eliminate an overheated condition of the combustion portion and to retain the heat radiated therefrom substantially uniform.

Referring to Figs. 1 and 2 the heating system of this invention is seen to include a housing 10 which is divided longitudinally thereof over substantially its entire length by a partition member 11 to provide a mechanical compartment 12 and a heating compartment. Within the heating compartment is a substantially cylindrically shaped combustion chamber 13, shown in development in Fig. 2, which is closed at one end by a cover plate 14 and at its opposite end by the bottom 16 of a substantially dish-shaped member 17. The member 17 defines in part an air supply chamber 18 which is in axial alignment with the combustion chamber 13.

The combustion chamber 13 is divided longitudinally thereof into four axially extending but connected passages 19a—19d by a partition member 21 of substantially X-shape (Figs. 2 and 3). The combustion chamber inlet 22 and outlet 23 are formed in the bottom portion 16 of the member 17 in communication with the passages 19a and 19d, respectively. Located within the inlet 22 is an air and fuel mixing means, indicated generally as 24, which is extended within the air supply chamber 18. The outlet 23 is provided with a tail or exhaust pipe assembly 26 extended into the air supply chamber 18 and outwardly therefrom through the end 27 of the housing member 10.

The outer wall or body portion of the combustion chamber 13 is integrally formed with alternately arranged peripheral portions 28 and doubled fin portions 29, which are angularly spaced about the combustion chamber and extended axially thereof. The side portions of the partition member 21 are located within certain ones of the fins 29 and retained therein in a fixed position relative to the combustion chamber body portion by welding or like means. The fins 29 have a sleeve 31 positioned about the outer ends thereof so as to form an annular passage 32 about the combustion chamber 13 for air to be heated.

The air to be heated is admitted into the passage 32 through an inlet 33 connecting the passage with the mechanical compartment 12 and is circulated through the passage 32 by a fan 34 located within the compartment 12 and mounted on a shaft 36 of an electric motor 37 (Fig. 2). The compartment 12 and air passage 32 are separated from the air supply chamber 18 by a sealing or partition member 38 extended transversely of the housing 10. From Fig. 2 it is seen that the air supply chamber 18 is defined by the dish-shaped member 17, the partition member 38, and the end 27 of the housing 10. Air circulated by the fan 34 is thus confined to travel within the compartment 12 and passage 32 and is discharged from the passage through an outlet 39 which is connected to a space to be heated.

The supply chamber 18 receives air from a fan 41 located therein and mounted on the motor shaft 36 which is journaled in the partition plate 38. An inlet 42 for the fan 41 is provided in the housing end 27. It is seen, therefore, that the fans 34 and 41 are operated by a common electric motor 37 and are mounted directly on the shaft 36 thereof.

The motor 37 is also utilized in the operation

of a fuel pump 43 which is illustrated in Figs. 2 and 4 as being of solenoid type. The breaker assembly 44 for controlling the energization of the pump 43 is operatively associated with the motor shaft 36. Fuel for the pump 43 is supplied thereto from a suitable source (not shown) through pipe 46, and is delivered through a pipe 47 to a fuel injection nozzle 48 formed as a part of the air and fuel mixing means 24. The pump 43, breaker assembly 44, motor 37 and fan 34 are thus all located within the mechanical compartment 12, which is provided with an inlet 49 for supplying either fresh or recirculated air to the fan 34 for delivery to the air passage 32.

The pump 43 (Figs. 4 and 5) includes a cylinder 70 of tubular form which is operatively associated with a tubular piston 71 of elongated construction. The cylinder 70 is provided in a suitable non-magnetic material, such as brass, while the piston is provided in a magnetic material, such as iron, movement of the piston in one direction being effected on energization of a solenoid 72 which is mounted about the cylinder 70, the piston 71 operating as a solenoidal core. Fluid enters the pump at the cylinder end 73 and is discharged therefrom at the cylinder end 74, the piston being operable substantially between the cylinder ends. The flow of fuel through the cylinder ends 73 and 74 is controlled by valve structures 76 and 77, respectively, while the fuel flow through the tubular piston 71 is regulated by a valve structure 78 carried in one end thereof. All of the valve structures are of a substantially similar construction so that similar numerals of reference are used to designate like parts. Thus as shown in Figs. 4 and 5 each valve 76, 77 and 78 includes a disc member 79, normally retained on a corresponding seat portion 81 by a corresponding spring 82.

All of the disc members 79 are lifted in the same direction away from their corresponding seats in response to the fuel pressures acting thereon.

In the operation of the pump the piston 70 is moved in one direction, namely, to the left as viewed in Fig. 4 by the magnetic action of the solenoid 72. A return movement of the piston 70, towards the right, is obtained by a spring 83 which is located in an expansible inlet chamber 84 formed between the valve structures 76 and 78. The solenoid 72 is selectively energized by the action of the breaker assembly 44. On movement of the piston 70 to the left, the chamber 84 is contracted to increase the pressure of the fuel in such chamber. This increased pressure seats the disc 79 of the valve assembly 76 to prevent any flow of fuel outwardly from the pump inlet, and lifts the disc 79 of valve assembly 78 to permit fuel from the chamber 84 to flow through the tubular piston 71 into an expansible outlet chamber 86 formed at the cylinder end 74, as indicated by the dotted line 87. On de-energization of the solenoid movement of the piston 70 toward the right, as produced by the spring 83, effects a suction pressure in the inlet chamber 84, due to its being expanded, whereby the valve structure 76 is opened to permit fuel to flow into the inlet chamber 84; the fuel admitted to the chamber 84 being at substantially supply line pressure. The fuel in the outlet chamber 86 is compressed due to such chamber being contracted, with the increase in pressure closing the valve structure 78 and opening the valve structure 77 to discharge the fuel from the pump. On reenergization of the solenoid the cycle of piston operation is repeated.

It is thus seen that all of the disc members 79 open in the direction of fuel flow and are operable in response to the fuel pressures produced in the expandable chambers 84 and 86 by the reciprocating action of the piston 71 in the cylinder 70. This action of the piston and disc members provides for a successive moving of the fuel through the pump, the fuel first being admitted into the inlet chamber 84 through the valve 76 on movement of the piston 71 toward the right, then passed through the valve 78 to the chamber 86 on movement of the piston toward the left, and finally ejected from the pump, through the valve 77 on movement of the piston toward the right. It is to be noted that the movement of the piston 71 toward the right provides for the drawing of fuel into the chamber 84 and the discharge of the fluid from the chamber 86 so that the suction action of the pump occurs concurrently with its ejection action.

The air and fuel mixing means 24, previously mentioned, includes a substantially tubular shaped housing member 51 which is closed at one end and open at the end 52 thereof with the passage 19a. A mixing chamber 53 is located at the closed end of the casing 51, and is separated from an equalizing chamber 54 by a plate member 56 having perforations 57 therein. The equalizing chamber 54 in turn is both defined and separated from the combustion chamber passage 19a by a heat insulating plate 58 having perforations 59 therein. Extended substantially axially through the casing 51 and projecting outwardly from the closed end thereof is a combination heating and igniting unit 61 including a resistance coil 62 supported in a spaced relation within a heat conducting tube 63 composed of copper or like material. The casing 51 and partition plate 56 are provided in a heat conducting material, such as copper or the like, and are in thermal connection with the combination unit 61 so as to readily receive heat therefrom. The combination unit 61 is adapted to heat the air and fuel mixing means 24 to at least a fuel vaporizing temperature to facilitate the mixing together of the air and fuel admitted therein, and to ignite such mixture for burning within the combustion chamber 13.

The fuel delivered to the fuel injection nozzle 48 by the pump 43 is directed into the mixing chamber 53, the fuel nozzle being located within the air supply chamber and mounted directly on the casing 51 at the chamber 53 (Fig. 2). A portion of the air for mixing with the fuel enters the nozzle 48 through ports 64 therein and travels with this fuel into the mixing chamber 53. Further air is admitted directly into the mixing chamber 53 through apertures 66 in the casing 51 and about the fuel nozzle 48. The fuel thus entering the mixing chamber 53 is heated to at least a fuel vaporizing temperature for intimate mixing with the air in such chamber by the function of the heating unit 61, the heat from which is transferred to the casing 51 and plate 56 in thermal connection therewith. Mixing is facilitated by the turbulence of the air in the mixing chamber. This vaporous mixture passes into the equalizing chamber 54 through the apertures 57 in the plate member 56. The equalizing chamber in conjunction with the insulating plate 58, which retards the mixture flow through the conditioning unit 24, acts to reduce turbulence in the mixture and to disperse the mixture substantially uniformly across the entire cross section of the casing 51 so that a mixture of substantially uni-

form fuel characteristics passes through the apertures 59 in the heat insulating plate 58 and into the igniting zone at the end 67 of the combination unit 61 which functions as a heat gun. In other words the heat developed by the coil 62 is projected outwardly from the unit end 67, the heat generated being dependent upon the watt input to the resistance coil 62. The mixture thus ignited is burned in the combustion chamber 13, 10 with the exhaust gases being discharged through the pipe assembly 26.

In Figure 6 there is illustrated a control circuit for operating the heater apparatus of Figs. 1 and 2 from a usual car battery indicated at 88. The motor 37 and coil 62 of the combination electrical unit 61 are series connected in a common circuit which from the battery 88 includes conductor 89, control switch 91, conductor 92, motor 37, conductor 93, coil 62 and a ground connection 94. 15 The circuit of the pump 43 from the battery 88 includes conductor 89, control switch 91, conductor 96, the breaker assembly 44, conductor 97, the pump 43 and a ground connection 98. Thus on opening and closing of the control switch 91 20 the motor 37, coil 62 and pump 43 are all operated and stopped together.

During the operation of the heater apparatus it is desirable, of course, that the combustion portion be operated to deliver a substantially uniform heat so that overheating thereof, resulting 30 for some reason from a failure in the flow of the air to be heated, or an increase in the temperature of such air, be eliminated. It is readily apparent that any overheating of the combustion chamber 13 might result in injury or damage to the heater apparatus as well as to objects adjacent thereto. In order to eliminate these dangers and to provide at all times for a safe operation of the combustion portion 13 the present invention 35 contemplates the utilization of the fuel system, including the pump 43 and fuel line 45, to provide a protective system which operates in response to the temperature of the heat of the combustion portion and/or the heat of the circulated air to control the rate of fuel feed to the mixing means 24 and hence to the combustion portion 13.

On operation of the heater apparatus the heat from the combustion chamber 13 is transferred 50 by conduction and radiation into the mechanical compartment so as to heat the parts located therein. These parts are normally cooled by the passage of the air to be heated which flows through the mechanical compartment 12, as has 55 been fully explained above. In one commercial embodiment of the invention the mechanical compartment 12 is of a length of about twelve inches and has a cross section about four inches square, with the air circulated therethrough by 60 the fan 34 being on the order of about 90 cubic feet per minute. The pump 43, in this embodiment, has a heatable mass of about one pound with all portions thereof being substantially heat conducting. As is best shown in Fig. 2 the pump 65 43 is arranged substantially intermediate the sides of the mechanical compartment 12 so as to be spaced a distance of about 2 inches or so from the combustion chamber 13. This pump operates to discharge fuel at the rate of about six cubic centimeters per minute, which fuel flow therethrough relative to its heatable mass is incapable of cooling the pump. In other words the mass of the pump is large relative to the amount of fuel flowing 70 through the fuel system so that heat is trans- 75

ferred from the pump to the fuel to increase the temperature thereof.

In the operation of the pump 43 a temperature providing for its normal operation is maintained by virtue of the cooling action thereon by the air to be heated. Thus, so long as the air to be heated is supplied at a temperature below a certain value, which maintains a normal operating temperature of the pump 43, the pump 43 will operate at full capacity to supply fuel to the conditioning means 24. However, if for any reason, the air to be heated becomes initially heated prior to its passage into the mechanical compartment 12, or while in the compartment 12, to a temperature which is insufficient to cool the pump to a normal operating temperature a vapor lock condition will be produced in the pump which operates to reduce the rate of fuel feed to the conditioning means 24 and hence to the combustion chamber 13. Since the fuel flow through the fuel system is incapable of retaining the same cooled at a normal operating temperature any changes in the condition of the air to be heated, as above noted, effects a vapor lock in the pump 43.

This vapor lock condition is the result of the fuel being heated to a temperature such that upon its entering the pump inlet chamber 84 at a reduced or suction pressure therein, fuel vaporization takes place to a degree depending upon its temperature and the suction pressure in the chamber 84. It is well known, of course, that the temperatures of the vaporization points for various liquids are usually given at atmospheric pressure. If the liquid is raised above this temperature and the pressure is also increased to retain the liquid in a liquid form, the liquid is said to be superheated, that is superheated relative to its initial temperature and pressure. When liquid in a heated state at a certain pressure is released into a pressure lower than such certain pressure, vaporization takes place to some extent immediately. The extent of the vaporization depends upon the heat available. This occurrence of vaporization is seen, therefore, to depend upon the initial pressure and temperature of the liquid and the pressure into which the liquid is released. In the present invention vaporization of the fuel results from the heating of the fuel at a pressure in the line, and the releasing thereof into the suction or vacuum pressure of the inlet chamber 84.

By virtue of the degree of vaporization being dependent upon the heat available the fuel supply system can be initially heated so as to provide for a small vapor lock action in the pump and a correspondingly small reduction in the rate of fuel supplied to the combustion chamber. However, should the temperature of the fuel supply system continue to increase above a value providing for such initial vapor lock action, the vapor lock action will correspondingly be increased to a maximum condition at which all of the fuel is vaporized. This maximum limit results in practically stopping the rate of fuel feed to the combustion portion so as to stop the operation thereof. The reduction in fuel feed to the combustion chamber 13 occurs because of the fact that the pump, when vapor lock is present therein, functions to pump a combination of liquid fuel and vaporous fuel, with its discharge capacity being reduced in direct proportion to the ratio of fuel vapor to liquid fuel. Thus referring to Fig. 4, on the suction stroke of the piston the chamber 84 is filled with a vaporous and liquid fuel mixture for passage into the outlet chamber 86. However, on compressing this mixture in the chamber 86, the vaporous fuel re-

turns to a liquid state so that liquid fuel is discharged from the pump. Since the liquid fuel in the chamber 86, is of lesser volume than the same amount of fuel which was in a vaporous and liquid state in the chamber 84, the available capacity of the pump is decreased in proportion to the amount of vaporous fuel initially present in the chamber 84. The pump operates, therefore, to vary the rate of fuel supply to the combustion chamber directly in response to the amount of heat radiated from the combustion chamber so as to provide an automatic fuel control for retaining the quantity of heat radiated from the combustion chamber substantially uniform at all times.

15 Since any overheating of the combustion chamber tends to create a maximum vapor lock condition in the pump the supply of fuel thereto is stopped so as to prevent a prolonged operation thereof in an overheated condition. In the commercial embodiment of the invention above noted the vapor lock action of the pump lags the operation of the combustion chamber relative to the quantity of heat radiated therefrom by a matter of about five or six minutes. The vapor lock action in controlling the fuel feed is thus relatively fast in its control of the heat condition of the combustion chamber.

As was previously mentioned the reduction in the rate of fuel supply to the combustion portion 13 is in direct proportion to the ratio of fuel vapor to liquid fuel initially present in the inlet chamber 24. The temperature of the fuel at the pump inlet, therefore, determines the extent to which vaporization will occur in the inlet chamber 24, and hence the amount of fuel pumped to the combustion portion 13. Thus as is noted in Figs. 1 and 2 that portion of the fuel line 46 within the mechanical compartment 12 is extended adjacent the partition wall 11 to facilitate its being heated from the combustion portion 13. Although both the temperature of the fuel at the pump inlet and the suction pressure within the chamber 24 determine the degree of fuel vaporization, the vaporization of the fuel is facilitated by increasing the temperature of the fuel rather than by increasing the degree of suction pressure. In other words fuel at 180° F. will vaporize at five inches of mercury more readily than fuel at a temperature of 80° F. at a vacuum pressure of seven inches of mercury. By heating a portion of the fuel line 46, therefore, the vapor lock condition in the pump 43 is made more immediately responsive to the heat condition in the combustion chamber 13, so as to appreciably reduce the period of lag between the occurrence of the vapor lock condition and the degree of heat applied to the system.

From a consideration of the description and drawings, therefore, it is seen that the invention provides a protective system for controlling the rate of heat radiated from apparatus including a combustion portion, in which the system for supplying fuel to the combustion portion is utilized and arranged relative to the combustion portion to control the rate of fuel feed thereto. The vapor lock condition in the pump can result from a heating of the pump to in turn heat the fuel therein, heating of the fuel alone prior to its entering the pump, or by the heating of both the pump and the fuel line. The cooling fluid for maintaining a normal operation of the fuel system can effect a vapor lock condition in the pump by its becoming heated above a temperature adapted to retain such normal operation, or by a complete stoppage thereof. It is obvious of course that the invention is not restricted to the solenoid

pump illustrated, but it is applicable for use with any pump which operates with a suction and working cycle.

Although the invention has been specifically described with reference to a preferred embodiment thereof it is to be understood that it is not so limited since modifications and alterations can be made therein which are within the full intended scope of the invention as defined by the appended claims.

I claim:

1. In a heater which includes a heat exchange structure defining a fuel combustion chamber; a liquid fuel supply system for delivering fuel to said combustion chamber, means for vaporizing a portion of the fuel traversing said system as the temperature of said structure rises above a given value, and means included in said system for delivering combustible fuel to said combustion chamber at a mass rate which gradually decreases with increase in the rate of vaporizing of said fuel by said last-named means.

2. In a heater which includes a heat exchange structure defining a fuel combustion chamber; a liquid fuel supply system for delivering fuel to said combustion chamber, means for vaporizing the fuel traversing said system at a rate which increases as the temperature of said structure increases from a given value, and means included in said system for delivering combustible fuel to said combustion chamber at a mass rate which varies inversely with the rate at which the fuel is vaporized by said last-named means.

3. In a heater which includes a heat exchange structure defining a fuel combustion chamber; a liquid fuel supply system for delivering fuel to said combustion chamber, means including parts of said structure and parts of said system arranged in heat transfer relationship for utilizing the heat of fuel combustion within said chamber to vaporize a portion of the fuel traversing said system as the temperature of said structure rises above a given value, and means included in said system for delivering combustible fuel to said chamber at a mass rate which gradually decreases with increase in the rate of vaporizing of said fuel by said last-named means.

4. In a heater which includes a heat exchange structure defining a fuel combustion chamber; a liquid fuel supply system for delivering fuel to said combustion chamber, means including parts of said structure and parts of said system arranged in heat transfer relationship for utilizing the heat of fuel combustion within said chamber to vaporize a portion of the fuel traversing said system as the temperature of said structure rises above a given value, means included in said system for delivering combustible fuel to said chamber at a mass rate which gradually decreases with increase in the rate of vaporizing of said fuel by said last-named means, and means for circulating air through at least one heat transfer zone between said structure and said system, thereby to prevent the vaporization of the fuel traversing said system until the temperature of said structure exceeds said given value.

5. In a heater which includes a heat exchange structure defining a fuel combustion chamber; a

liquid fuel supply system for delivering fuel to said combustion chamber, means including parts of said structure and parts of said system arranged in heat transfer relationship for utilizing the heat of fuel combustion within said chamber to vaporize the fuel traversing said system at a rate which increases as the temperature of said structure increases from a given value, and means included in said system for delivering combustible fuel to said combustion chamber at a mass rate which varies inversely with the rate at which the fuel is vaporized by said last-named means.

6. In a heater which includes a heat exchange structure defining a fuel combustion chamber, a liquid fuel supply system for delivering fuel to said combustion chamber, means including parts of said structure and parts of said system arranged in heat transfer relationship for utilizing the heat of fuel combustion within said chamber to vaporize the fuel traversing said system at a rate which increases as the temperature of said structure increases from a given value, means included in said system for delivering combustible fuel to said combustion chamber at a mass rate which varies inversely with the rate at which the fuel is vaporized by said last-named means, and means for circulating air through at least one heat transfer zone between said structure and said system, thereby to prevent substantial vaporization of the fuel traversing said system until the temperature of said structure exceeds said given value.

7. In a heater which includes a heat exchange structure defining a fuel combustion chamber; a liquid fuel pump and a conduit fluid connected with the inlet side of said pump, means including a part of said structure and a portion of said conduit arranged in heat transfer relationship for utilizing the heat of fuel combustion within said chamber to heat the fuel traversing said conduit and thus produce at least partial vaporization of said fuel within said pump, and means comprising said pump for delivering combustible fuel to said combustion chamber at a mass rate which gradually decreases with increase in the rate of vaporizing of said fuel within said pump.

8. In a heater which includes a heat exchange structure defining a fuel combustion chamber; a liquid fuel pump and a conduit fluid connected with the inlet side of said pump, means including a part of said structure and a portion of said conduit arranged in heat transfer relationship for utilizing the heat of fuel combustion within said chamber to heat the fuel traversing said conduit and thus produce at least partial vaporization of said fuel within said pump, means comprising said pump for delivering combustible fuel to said combustion chamber at a mass rate which gradually decreases with increase in the rate of vaporizing of said fuel within said pump, and means for circulating air through the zone of heat transfer between said part of said structure and said portion of said conduit, thereby to prevent substantial vaporizing of the fuel within said pump until the temperature of said structure exceeds a predetermined value.

HARRY B. HOLTHOUSE.
